CLAIM

We claim the ornamental design for a step-on wastebasket, as shown.

DESCRIPTION

FIG. 1 is a perspective view from the top of the step-on wastebasket with the top opened,

FIG. 2 is an elevational view of the front of the step-on wastebasket with the top closed,

FIG. 3 is an elevational view of the rear of the step-on wastebasket with the top closed,

FIG. 4 is an elevational view of the left side of the step-on wastebasket with the top closed,

FIG. 5 is a top side view with the top closed; and,

FIG. 6 is another perspective view from the bottom with the top closed.
